UNITED STATES PATENT OFFICE

WILHELM RIEHM, OF AUGSBURG, GERMANY, ASSIGNOR TO THE FIRM MASCHINEN-FABRIK AUGSBURG-NUERNBERG, AKTIENGESELLSCHAFT, OF AUGSBURG, GERMANY, A CORPORATION OF GERMANY

DOUBLE-ACTING GAS ENGINE WITH SLOT SCAVENGING

Application filed May 25, 1928, Serial No. 280,555, and in Germany June 18, 1927.

This invention relates to internal-combustion engines and more particularly to two-stroke cycle engines.

One object of the invention is the provision, in a two-stroke cycle engine having a piston controlled exhaust valve and having slotted fuel inlet and scavenging air ports, of an additional exhaust controlling means.

Other objects and advantages of the invention will be apparent from the following description and from the accompanying drawings in which—

The drawing is a longitudinal sectional view through the cylinder of a double-acting two-stroke cycle engine constructed in accordance with this invention.

This invention is preferably employed in connection with a two-stroke cycle engine adapted to operate upon an explosive mixture, a double-acting engine being illustrated in the drawing.

For purposes of easier description, the figure of the drawing is somewhat diagrammatic in character and only one-half of a double-acting engine is shown, it being understood that the remaining half is similar in construction to that illustrated.

As shown, the engine cylinder *b* which may be supplied with means such as spark plug *h*, for causing the ignition of the compressed fuel mixture, is provided with exhaust ports or slots *d* through which the burnt gases travel from the combustion chamber. Scavenging air ports or slots *a* are provided in the cylinder walls and in a plane spaced away from the exhaust ports. The cylinder walls are also provided with fuel inlet ports or slots *c*, arranged in a plane spaced from the scavenging air ports *a*. Operating within the cylinder is a piston which is adapted to open and close the various ports. The ports *a*, *c* and *d* are arranged, as shown, at one side of the cylinder *b* so that the scavenging air entering the cylinder may

flow along the concave upper side of the piston, and along the cylinder wall opposite the inlet slots toward the top of the cylinder. It then reverses as it flows over the curved top of the cylinder and flows toward the exhaust slots *d*, pushing the exhaust gases ahead

of it. The charge mixture follows the path of the scavenging air, this charge mixture comprising a mixture of fresh gas introduced through the inlet slots *c* and air introduced through the air slots *a*. Proceeding ahead of the charge mixture there is therefore a stratum of clean scavenging air, which prevents mixing of the charge mixture and the exhaust gases. This air stratum, indicated at *e* in the drawing, reaches the exhaust slots *d* ahead of the charge mixture which is indicated by the crossed lines.

To prevent the loss and waste of scavenging air and also the loss and waste of combustible mixture which might otherwise be forced through the exhaust slots *d* by the incoming stream as well as by the forwardly moving piston even after the fuel inlet slots close, the entire exhaust is controlled by a means *g* independently of the piston. This means *g* preferably comprises a quick closing valve between the exhaust passage *f* common to the various exhaust slots *d*, and the outside air. This valve *g*, is mechanically connected to the piston so as to rotate in timed relation with the piston operation so that the passage *f* will be closed every second stroke of the piston while the clean air stratum *e* is escaping from the ports *d* and before the fresh fuel mixture reaches these exhaust slots. In this manner the escape of the fuel mixture is prevented, and the exhaust of the gases from the cylinder is controlled to obtain the maximum economy of both fuel and scavenging air.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A two-stroke cycle engine comprising a cylinder having an exhaust port, a piston in said cylinder adapted to open and close said port, separate piston controlled scavenging and fuel inlet ports in said cylinder, said ports being arranged adjacent so that the

scavenging air port is opened just before the fuel inlet port is opened to provide a small stratum merely of scavenging air between the fuel mixture and the exhaust gases during scavenging, and a valve for controlling the escape of the exhaust gases from said cylinder to close the exhaust passage while the scavenging air stratum escapes from the cylinder.

- 10 2. A two-stroke cycle engine of the character described comprising a cylinder having an exhaust port, a scavenging air port and a fuel inlet port in the wall thereof and at the same side of the cylinder to provide for reverse scavenging flow, a piston operating within said cylinder to control said ports successively so that the exhaust port is first opened and then the scavenging air ports are opened just before the gas inlet ports to provide a scavenging air stratum between the burnt gases and the new mixture charge, and a valve for controlling the exhaust from said cylinder to close the exhaust passage while the scavenging air stratum escapes from the cylinder.

15 20 25 In testimony whereof I have affixed my signature.

WILHELM RIEHM.
